UNITED STATES PATENT OFFICE

WILLIAM R. BLAIR, OF WASHINGTON, DISTRICT OF COLUMBIA

SEAGOING CRAFT

Application filed May 16, 1930. Serial No. 453,007.

(GRANTED UNDER THE ACT OF MARCH 3, 1883, AS AMENDED APRIL 30, 1923; 370 O. G. 757)

The invention described herein may be manufactured and used by or for the Government for governmental purposes without the payment to me of any royalty thereon.

This invention relates to a sea going craft of that type having the load supporting hulls positioned beneath the disturbed sea surface and the load itself positioned well above the sea surface by strut members which do not 5 interpose sufficient resistance to the waves to produce instability of the craft.

Objects of this invention are to provide a craft of the type mentioned, in a practical form, which is extremely stable in heavy seas; 15 which automatically compensates the lift of the supporting hulls, which will not list if load is applied unevenly to the craft as a whole, and which will maintain its proper position or level in the water regardless of 20 the weight of the load carried.

An important object of the invention is to regulate the automatic compensating means in such a manner that the submerged load-supporting hulls or floats will be maintained 25 at a predetermined level below the sea surface and at a sufficient depth to minimize the effects of wave action and surface currents. Other objects of the invention will appear as the description proceeds.

The drawings accompanying this application illustrate diagrammatically one method of effecting the above objects, Fig. 1 being a 30 side view of the craft in the water showing a view of the same partly in cross section; 35 and

Figure 2 being a bottom plan view of Figure 1.

In these drawings there is shown load supporting hulls 1 positioned beneath the disturbed sea surface, and having upwardly extending struts 2, which project a load carrying platform 3 well up out of reach of any waves. To propel the craft through the 40 water any type of motive power may be used 45 the power units 4 connected to propellers 5 being merely suggestive.

Although only one hull is shown in cross section, it is to be understood that the description which follows applies equally to all 50 the hulls. The cross sectioned one shows a

ballast chamber 6 communicating with the sea through an opening 7 and with a compressed air supply 8 through valves 9, and 10, the valves 10 operating as an air release. The valves 9 and 10 are controlled either by hand or preferably by electric motors 11. These motors are energized by a current source, in this case a battery 12 which is connected in circuit, through switches 13, the same being located, one above and one below the mean level which it is desirable the craft as a whole should maintain. Line $x-x$ of Fig. 1 indicates the mean level of the sea surface which preferably should be maintained by the craft. The switches 13 are operable by the water level maintained in a tube 14 which is open to the sea and preferably has a restricted water entrance 15 to prevent undue oscillation of the water in the tube. It will be seen that as the craft settles because of an increase in load, the valves 9 will be operated by the rise of water in the tubes 14 operating the upper of the switches 13 and will allow compressed air from the supply 8 to force water out of the hulls' ballast chambers 6 and thus increase their buoyant force. If, on the other hand, the craft rises because of a reduced load the lower of the switches 13 will operate to release air from the ballast chamber through the release valves 10, allowing water to enter 60 the same and decreasing their buoyant force, the valves 9 being closed.

Preferably the hulls 1 have their ballast chambers interconnected by hollow members 16 through valves 17 for the purpose of equalizing the pressures existing in all to create an ever upward thrust of each. When the craft is being loaded and unloaded there is apt to be an uneven placement of the load causing the craft to list and in this case the valves 17 are closed, allowing the hulls to increase or decrease their buoyant force individually to compensate for unevenness of load. This might also be desirable in case of an accident to one of the hulls.

The foregoing description is brief and the drawings diagrammatic but one skilled in the art may readily reduce the same to concrete form to evolve a craft which will accomplish the objects as proposed, this being

in accordance with the requirements of the U. S. patent statutes; but it is to be understood that the embodiment of the invention here disclosed is to comply with same and is not intended to limit the scope of the appended claims.

Rudders are preferably used to control the direction of movement of the craft, one set being shown at 18 by way of example. Fins 10 or rudders may also be employed as at 19 to assist in maintaining the craft at a constant depth or level when under movement, and also to promote the stability of the craft.

I claim:

15 1. A sea going craft comprising a load-carrying superstructure; a plurality of supporting hulls positioned in the water beneath the disturbed sea surface; struts connecting said superstructure and supporting hulls, 20 and adapted to project with said superstructure above the sea surface; and means positively operated with each of said hulls to control their buoyancy individually.

2. A sea going craft comprising a load-carrying superstructure; a series of supporting floats adapted to be submerged in a position beneath the disturbed sea surface; struts connecting said superstructure and supporting hulls, and adapted to project 30 above the sea surface; fluid carrying means between said struts and floats; fluid supply means and means responsive to load variations and controlled by fluctuations of the mean level of the sea surface to positively 35 actuate said fluid supply means and automatically compensate the lift of said supporting floats.

3. A sea going craft comprising in combination a load carrying component; a plurality of submerged hulls having connecting struts adapted to support said load carrying component above the disturbed sea surface and having fluid communication with said hulls; fluid means positively operative with 45 each of said hulls and struts and responsive to load variations to automatically compensate the lift of said hulls.

4. A sea going craft comprising a load-carrying superstructure; a substructure including a plurality of supporting hulls submerged beneath the sea surface; struts connecting said superstructure and substructure; means for connecting said hulls and struts to permit complete fluid intercommunication; fluid control means operative 50 with each of said hulls to control their buoyancy separately; and supplemental fluid control means to positively equalize the air pressure in all of said hulls.

5. A sea going craft comprising a load-carrying superstructure; a supporting substructure including a plurality of floats adapted to be submerged beneath the disturbed sea surface, each of said floats comprising an upper compartment having con-

stant buoyancy and a lower compartment having variable buoyancy; and means responsive to load variations on said superstructure and positively operative with said lower compartment to regulate the buoyancy of 70 each of said floats.

6. A sea going craft comprising a load-carrying superstructure; a plurality of supporting hulls adapted to be submerged beneath the disturbed sea surface; hollow 75 struts connecting said superstructure and supporting hulls, and adapted to project with said superstructure above the sea surface; a tube to indicate the mean level of the sea surface vertically disposed within each 80 of said hulls and struts, said tube having communication with the sea at its lower end and open to atmosphere at its upper end; fluid supply means for each of said hulls to regulate buoyancy and electric circuits operative therewith; and switches in each of said circuits so positioned in each tube as to alternately respond to fluctuations of water level to control the operation of the fluid supply 85 means.

7. A sea going craft comprising a load-carrying superstructure; a supporting substructure including a plurality of supporting floats adapted to be submerged beneath the disturbed sea surface, each of said floats 95 having a variably buoyant ballast chamber; and fluid control means operative with each of said chambers to vary their lift selectively to compensate for load variations on said superstructure.

In testimony whereof I affix my signature.

WILLIAM R. BLAIR.
